US0D1056915S

(12) **United States Design Patent** (10) Patent No.: **US D1,056,915 S**
(45) Date of Patent: ** Jan. 7, 2025

(54) **IMAGE READING APPARATUS**

(71) Applicant: **Canon Denshi Kabushiki Kaisha**,
Saitama (JP)

(72) Inventors: **Hanako Oosawa**, Tokyo (JP); **Misato Machida**, Tokyo (JP)

(73) Assignee: **Canon Denshi Kabushiki Kaisha**,
Saitama (JP)

(**) Term: **15 Years**

(21) Appl. No.: **29/871,727**

(22) Filed: **Feb. 27, 2023**

(30) **Foreign Application Priority Data**

(57) **CLAIM**

The ornamental design for an image reading apparatus, as shown and described.

DESCRIPTION

FIG. 1 is a perspective view of an image reading apparatus according to our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The evenly spaced broken lines shown in the figures indicate portions of the image reading apparatus that form no part of the claimed design. The dash-dot broken lines depict the boundaries of the claim and form no part thereof.

1 Claim, 7 Drawing Sheets
